UNITED STATES PATENT OFFICE.

LOUIS ROSEN, OF EDGEWATER, COLORADO.

MECHANICAL MOVEMENT.

1,425,902.

Specification of Letters Patent. Patented Aug. 15, 1922.

Application filed August 1, 1921. Serial No. 488,859.

To all whom it may concern:

Be it known that I, LOUIS ROSEN, a citizen of the United States, residing at Edgewater, county of Jefferson, and State of Colorado, 5 have invented certain new and useful Improvements in Mechanical Movements; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to a mechanical movement of the type by which oscillatory movement can be converted into rotary movement in one direction and has special reference to a rolling chair for invalids in 20 which the chair is propelled by means of power derived from the rocking motion imparted thereto by the back and forth movement of the invalid's body.

It is frequently the case that cripples and 25 invalids who have lost the use of their limbs nevertheless retain a comparatively strong and active body and that they can rock themselves to and fro with considerable force. Although chairs of various kinds 30 are made for the use of invalids and cripples, some operated by the hands alone and others by the feet alone, yet as far as I am aware there are no chairs made that can be operated by the rocking of the body 35 alone.

It is the object of my invention to provide a rolling chair that can be operated by cripples or invalids who have lost the use of their limbs and by means of which 40 they may be able to move from place to place by power derived from the movement of their bodies.

My invention can be best understood by reference to the accompanying drawings 45 in which—

Fig. 1 is a side elevation of my rolling chair with parts broken away.

Fig. 2 is an end elevation partly broken away and part in section taken on line 2—2 50 Fig. 1.

Fig. 3 is a detail view taken on line 3—3, Fig. 2.

Fig. 4 is a side elevation of a boat equipped with my propelling device suitably 55 modified, and

Fig. 5 is an end elevation of the boat shown in Fig. 4.

The same reference numerals will be used to indicate the same parts throughout the several figures.

In Fig. 1, which illustrates the preferred embodiment of my invention, 1 represents my improved rolling chair in its entirety, the chair member 2 which is provided with the usual seat, back and arm rest, is pivotally mounted at 3 between the two sides 4 and 5 of the main supporting frame, which is indicated as a whole by the numeral 6. The supporting frame 6 is mounted on three wheels F, R and R' of which F is the front 70 or steering wheel and R and R' are the rear wheels, one of which is keyed to the axle 7 and serves as the driver. The front wheel F is mounted on a spindle 8 by which means it is secured to the ends of the forked member 9 which has a shank 10 extending through an inwardly projecting bearing 11 secured to frame 6. Secured to the top of shank 10 is a universal joint 12 to which a steering post 13 bearing a steering wheel 14 is connected. The lower portions of frames 4 and 5 are provided with bearings 15 and 16 in which is rotatably mounted the axle 7, ball or roller bearings being employed 75 in the usual way.

Keyed to the axle 7 on the inner side of bearings 15 and 16 are gear wheels 17. Rotatably mounted on the axle 7 and held in place thereon by means of collars 18 are two gear wheels 19 and 20. A ratchet mechanism is provided between gear wheels 17 and gear wheels 19 and 20 in order that the gears 19 and 20 when turned in a direction that would cause the chair to move backward, will be freely rotatable and when rotated in the opposite direction will engage with the gears 17 and rotate them. Any suitable ratchet mechanism may be used but, as an example, I have shown one side 90 of wheels 19 and 20 provided with arcuate 95 grooves having one end of considerable depth and a ball 22 in each of said grooves, the incline of the grooves being such that when the wheel is to act as a driver the deepened end of the groove will travel ahead and thus permit the balls to roll up on the shallow portion and become wedged against the 100 surface of gears 17. Mounted in suitable bearings in the lower portion of frame 6 is a second shaft 23 which has non rotatably se- 105

110

cured thereto, near the ends thereof, gear wheels 24 which mesh with gear wheels 17 but are somewhat larger in diameter. Rotatably secured to shaft 23 and held in place against the sides of wheels 24 by means of collars 18, or other suitable means, are gear wheels 25 and 26, which are identical with gear wheels 19 and 20. A ratchet mechanism similar to the one employed between wheels 19, 20 and wheels 17 is provided between wheels 25, 26 and wheels 24. Secured to the bottom of the chair portion 1 by means of bolts 27 are two gear sectors 28 which are pivoted on shaft 3 and have their gear teeth engaging with gears 19 and 25 and 26 respectively in the manner indicated in Fig. 3. Shafts 3, 7 and 23 form the vertices of an isosceles triangle and as sectors 28 are pivotally mounted on shaft 3, their geared peripheries are always in mesh with gears 19 and 25 and 20 and 26 as pointed out above.

One of the rear wheels only is keyed to shaft 7 while the other is freely rotatable thereon, the reason for this being that in turning a corner one traverses a greater distance than the other and that, therefore, relative rotation between the wheels is necessary.

30 The operation of my device is as follows:

Let us suppose that a person is sitting in the chair 1 with his hands grasping the wheel 14 and his feet resting on the upper surface of frame 6 and let the person so seated move his body backwardly, he will thereby move the chair backwardly about the pivot 3 and the gear sector 28 will move forwardly in the direction of arrow X (Fig. 3). Gear wheels 19 and 25 will at the same time be rotated in the direction indicated by the arrows shown in full. When gear wheel 19 is rotated in the direction indicated by the arrow shown in full, balls 22 will be moved to the shallow portion of groove 21 and become wedged between the bottom of the grooves and the side of wheel 17, locking the two wheels together and causing them to rotate as one. Gear wheel 17 will, of course, cause gear wheel 24 to rotate in the direction indicated by the broken arrow (Fig. 3). As gear sector 28 is in engagement with the teeth of gear 25, the latter will rotate in the same direction as gear 19. The clutches between the two set of gear wheels are so related that when the one between gears 19 and 17 is operative the one between wheels 24 and 25 will be inoperative and vice versa. When the chair has reached the limit of its backward rotation 60 the operator will incline his body forwardly and sectors 28 will move rearwardly in the direction indicated by arrow Y. The clutch between wheels 24 and 25 will now become operative and the clutch between wheels 17 and 19 inoperative whereby shaft 7 will be

rotated, through the medium of gears 25, 24 and 17, in the same direction as before. From the above it will be noticed that the chair will be moved in the same direction regardless of the direction in which the 70 chair moves about the pivot 3.

I have shown gear 24 somewhat larger in diameter than gear 17 while gears 19 and 25 are of equal diameter, the reason for this is that we have the greatest propelling power 75 exerted when the chair is rocked backwardly in starting and as the chair is gotten underway, the forward rocking of the chair acts through the greater gear ratio with less force but with greater speed.

80 I have shown my chair as equipped with two gear sectors 28 and a duplicate set of driving gears but it is evident that my chair will operate with one gear sector and one set of gears and I do not intend that the disclosure, which shows the driving gears in duplicate, shall be understood as a limitation in this respect but merely as illustrative.

85 My device is especially well adapted to 90 be applied to boats and canoes for propelling the same and in Figs. 4 and 5 I have shown a boat equipped with a propelling device embodying the principle of my present invention, but modified slightly 95 to adapt it to this use. Boat 100 has attached near the center thereof a propelling device which is indicated as a whole by the numeral 101: this device is substantially the same as the one used in connection with 100 my chair. The wheels of the chair have been replaced by paddle wheels 102 which are both keyed to the shaft 103 instead of one only, as in the case of the chair. In place of the chair I have substituted a 105 frame 104, each end of which is provided with a bar 106 to be grasped by the hand of the operator in the manner shown. Frame 104 is pivotally mounted on shaft 107 and has connected to each side thereof 110 two segmental gear members 28, whose teeth cooperate with a set of gears in the manner shown in Figs. 1, 2 and 3 in which figures shaft 7 corresponds to shaft 103 in Fig. 4. The power transforming and transmitting gearing has not been shown in detail in Figs. 4 and 5 but it is to be understood that the same arrangement is to be employed here as is described in connection with the chair.

115 The uses specifically enumerated are by no means the only ones to which my device is adapted. It can be embodied in self propelled vehicles for children, in toys of various kinds and can be used to convert oscillatory movement into rotary movement in one direction wherever it is found desirable to do so.

120 I desire to point out that when my mechanism is embodied in a rolling chair the chair 130

can be used in the same manner as any ordinary rolling chair, for the reason that when the chair is pushed ahead the ratchets will not operate and hence the chair portion 5 will remain stationary.

Having described my invention what I claim as my invention is:

1. A rolling chair comprising a supporting frame (6), a guide wheel (F) pivotally attached to said frame (6) means (12, 13, 14) for controlling said guide wheel, a pair of supporting wheels (R, R') rotatably attached to said frame, a chair (1) supported on pivots (3) spaced from but parallel 15 with the pivots (7) upon which said supporting wheels rotate and adapted to be oscillated back and forth about its pivot, and means comprising a gear sector (28) attached to said chair and engaging with 20 two gear wheels (19, 25) rotatably connected to two parallel spaced pivots (7, 23), cooperating gear wheels (17, 24) mounted on said last named pivots, and ratchet means between the gears on each 25 pivot, whereby the oscillatory movement of said chair will be changed to a rotary movement in one direction and transmitted to one of said supporting wheels for the purpose of propelling said rolling chair 30 in a forward direction.

2. A rolling chair comprising a supporting frame (6) a guide wheel (F) pivotally connected thereto, means (12, 13, 14) for controlling said guide wheel, an axle (7)

pivottally connected to said frame, a pair 35 of supporting wheels (R, R') mounted on said axle one of said wheels being rotatably secured to said axle and the other non-rotatably attached thereto, a second axle (23) mounted in said frame and parallel 40 with said first named axle, a gear (17) non-rotatably mounted on said axle (7) a second gear (19) also mounted on said axle in juxtaposition to said first named gear (17), ratchet means between said gears, a 45 gear (24) mounted on said second axle and engaging with the first named gear (17), a second gear (25) mounted on said second named axle (23), ratchet means between the two gears (24, 25) on said second named axle, a third axle (3) mounted in said frame and spaced equidistantly from each of the two first named axles, a 50 gear sector (28) pivotally mounted on said last named axle and engaging with one 55 gear on each of the first named axles, and a chair secured to said gear sector, and adapted to oscillate the latter about its pivot on said third axle, said gears and ratchets having such relation one to the 60 other that the oscillatory motion of said gear sector about its pivot will be transformed into rotary motion in one direction and transmitted to said first named axle.

In testimony whereof I affix my signature.

LOUIS ROSEN.
